[57] **CLAIM**

The ornamental design for a combined sterilizer and storage tube for medical instruments, as shown and described.

DESCRIPTION

FIG. 1 is a perspective view of a combined sterilizer and storage tube for medical instruments according to the present invention;

FIG. 2 is a top view thereof;

FIG. 3 is a bottom view thereof;

FIG. 4 is a right side view thereof;

FIG. 5 is a left side view thereof;

FIG. 6 is a front view thereof;

FIG. 7 is a rear view thereof; and,

FIG. 8 is a perspective view of the combined sterilizer and storage tube for medical instruments in a mounted condition, the dotted lines represent a medical instrument, support wall and screw fasteners, which are not part of Applicant's invention.
